ANTENNA HOUSING

Aylwin R. Booker, 4887 Palo Drive,
Tarzana, Calif. 91356

Filed Mar. 13, 1967, Ser. No. 6,186

Term of patent 14 years

(Cl. D26—14)

Fig. 1.

Fig. 2.

Fig. 3.

FIGURE 1 is a perspective view of an antenna housing showing my new design;

FIGURE 2 is a top plan view with some of the rod members in a retracted position; and

FIGURE 3 is a side view thereof.

The dominant features of my design reside in the portions shown in full lines.

I claim:

The ornamental design for an antenna housing, substantially as shown and described.
